UNITED STATES PATENT OFFICE.

ZACHARIAH T. GAPEN, OF GALESBURG, ILLINOIS.

BARREL ROLLING AND CENTERING DEVICE.

SPECIFICATION forming part of Letters Patent No. 781,513, dated January 31, 1905.

Application filed February 13, 1904. Serial No. 193,478.

To all whom it may concern:

Be it known that I, ZACHARIAH T. GAPEN, a citizen of the United States, residing at Galesburg, in the county of Knox and State of Illinois, have invented certain new and useful Improvements in Barrel Rolling and Centering Devices, of which the following is a specification.

This invention relates to that class of devices especially designed for rolling barrels from place to place, as in warehouses, breweries, distilleries, flour-mills, and for local transportation.

The primary object of the invention is to produce a simple, strong, and efficient device for "centering" the heads of the barrels, whereby they will when pushed or pulled from place to place or up an inclined plane roll exactly in the direction desired and not tend to roll at an angle or to one side.

Another object of the invention is to provide a device whereby the barrel, keg, or cask need not be touched by the hand or foot of the operator when being rolled from place to place, or, in other words, from one place to another.

It is a well-known fact that wet, dirty, or greasy barrels, and this is especially applicable to pickle-barrels, are difficult to manage, (more so in cold weather,) either by rolling them by the hands or "kicking" them, as they are inclined to roll or turn at an angle from the direction in which it is desired to have them go. This is especially troublesome when they are on a narrow runway, wherefrom they are liable to fall. When the processes familiarly known to the trade as "kicking" and "spiking" are resorted to, the barrel-hoops are frequently loosened and the staves splintered or broken. When rolled by hand, the painful and injurious position of stooping becomes necessary and imperative. Either of these methods is slow and tedious and involves a great waste of time. By the use of my improved device all of these objectionable features are provided against and obviated.

A further object of my invention is to provide means whereby the operation of local

handling, either by pushing or pulling the barrel, may be greatly facilitated.

Other objects of my invention consist in novel structural features and combinations of parts, the operation of which parts separately and in combination will be found hereinafter fully described, and the novel combinations of which parts are specified in the claims of this specification.

Mechanism showing the arrangement, connection, and mutual relationship of the several parts of my improvement are illustrated in the accompanying drawings, in which—

Figure 1 is a face elevation showing the device extended; Fig. 2, a side elevation, partly broken away; Fig. 3, a face elevation showing the device contracted and the clutches engaged with the heads of the barrel; Fig. 4, a perspective of centering-guides; Fig. 5, a plan view; Fig. 6, a sectional view, and Fig. 7 another sectional view.

Referring to the drawings by letters, the same reference-letter indicating the same part in the different figures thereof, A represents an arched or inverted-U-shaped frame or loop and is constructed of any material capable of being flexed, sprung, or bent, but preferably of wood.

B is a rod screw-threaded through a nut C, secured to the upper central portion of the frame A and at its lower end secured, as shown at B² or in any desired manner, to a spring cross-plate C', which latter is connected at its ends to the lower portions of the frame A, as shown at Figs. 1 and 3, or in any other preferred or desired manner.

D D are toothed clutches loosely journaled at E in bearings in plates F F on the lower ends of the frame A and held therein by split keys a.

d' (shown in dot-lines at Figs. 1 and 3) represents a barrel or cask.

G G are pairs of depending wires terminating at their lower portions in loops or guides G' G', conforming in shape to the contour of the bulge of the barrel, and are connected by wires g g, conforming in contour to the longitudinal shape of the staves thereof. The guides G G preferably pass on either side of the

spring cross or connecting plate C' and near their upper portions are connected by plates H H for limiting their upward movement and by plates J J for limiting their downward movement. Their ends are then brought together to form handles K K for facilitating the use of the device in operation.

For the purposes of this specification I will designate the parts lettered G G, G' G', g g, 10 H H, J J, and K K the "centering device."

L L are flat springs fixed to the inner side of the frame A, and M M are turn-buttons fixed to the outer side thereof, both as shown and for purposes hereinafter described.

15 In operation, the parts being in the relative positions shown at Fig. 1, when it is desired to roll the barrel from one place to another and the vertical distance from the centering-guides G' G' to the central pins D' of the 20 clutches (said pins being slightly longer than those surrounding them) being equal to the distance from their positions on the bulge on the barrel vertically to the center of the heads thereof, the operator will lift the device by 25 means of the handles K K and place it centrally lengthwise of the barrel, with the loops or guides G' G' and their connecting-wires resting on the bulge thereof. It will readily be seen that the heads of the barrel a' will thus 30 be automatically "centered" by the clutches D. The screw-threaded rod B is then turned by its handle or lever B' in a direction such as to raise the middle or central portion of the spring-plate C', thus contracting it to the position shown in Fig. 3 and bringing the lower 35 portions of the frame A closer together, when the points or pins of the clutches will partially enter the heads of the barrel around their centers, and the pressure of the wood on said points or pins will automatically lock the 40 rod B in its position shown at said figure. The barrel-heads being thus centered, the turn-buttons are released from engagement with the plates J J, whereby the centering device 45 will be thrown upward, as shown at Fig. 3, and free from contact with the sides of the barrel by the action of the springs L L on the plates H H on the depending loops G G, in which 50 position the barrel is ready to be rolled. When it is desirable to release the barrel, the rod B is screwed downward to the position shown in Fig. 1, thus expanding the spring and thereby 55 the lower portions of the frame, and releasing the clutches from the heads of the barrel.

55 It will be seen that my device may be used with either face thereof toward the operator and that the thread on the rod may be either a right or a left hand one. It is, however, preferably double-threaded, for two purposes— 60 viz., strength and rapidity in use. It will further be seen that by the use of my device the operator has complete and full control of the barrel to push, pull, turn, or guide it in any direction.

The advantages of the invention will be apparent, and the operation will be understood from the foregoing description, it being particularly noted that various changes may be made in the details of construction without departing materially from the general idea involved.

Having thus described my invention, what I claim as new, and desire to secure by Letters Patent, is—

1. In a device of the class described, a frame or loop, a spring cross-plate connecting the lower parts of said frame or loop, a screw-threaded rod connected to the cross-plate and to the loop, clutches at the lowermost portions of the frame or loop, and a centering device, 75 all substantially as described and for the purpose specified.

2. In a device of the class described, and in combination, a contractible inverted-U-shaped frame or loop, a spring-plate connecting the lower portions of the frame or loop, and adapted to be sprung upward at its median portion, a rod screw-threaded through the central upper portion of said frame and at its lower end connected to said spring-plate, 85 clutches on said frame, and a centering device mounted on and carried by said frame, all substantially as shown and for the purposes specified.

3. In a device of the class described, an inverted-U-shaped loop or frame contractible at its lower portions, a barrel-centering device mounted thereon, turn-buttons for locking said centering device in its lowermost position, springs for automatically raising said device when the turnbuckles are released, and means for engaging the ends of the frame with the heads of a barrel or cask.

4. In combination in a barrel-rolling device, a contractible inverted-U-shaped frame, 105 a centering device mounted thereon, the upper portions of which form handles, means for limiting the upward and downward movements of said centering device, and clutches at the lower inner portions of said frame. 110

5. In a device of the class described, an inverted-U-shaped frame contractible at its lower portions, a spring cross-plate connecting said lower portions, a rod screw-threaded through a nut on the upper part of said frame 115 and secured to the cross-plate substantially as shown, whereby said cross-plate may be raised or lowered for the purpose described, an adjustable centering device, and clutches on the inner and lower ends of said frame, all in combination substantially as described and for the purposes set forth.

6. In a device of the class described, a frame A, a rod B screw-threaded through a nut C on the central upper part of the frame, said rod having a handle or lever B' rigidly secured thereto at its upper end, a spring cross-plate loosely connected at its median part to 125

the lower end of said rod and at its ends to the lower portions of the frame A, a centering device partly beneath said spring cross-plate, the upper ends of said centering device being extended to form handles K, plates H and J on said centering device to limit its upward and downward movements, respectively, springs L, L for automatically raising said centering device, turn-buttons M, M for locking said centering device in its lowermost position, and clutches D journaled in the lower end parts of the frame, said parts all operating together substantially as described and for the purposes specified.

15 7. In a device of the class described, a dome

or arch shaped frame A, expandible and contractible at its lower portions, a spring-plate connecting said lower portions, a rod screw-threaded through a nut on the central upper part of said frame and having its lower portion engaged with the central portion of said spring-plate for the purpose specified, and clutches journaled in the lower ends of the frame, substantially as shown and for the purpose specified. ²⁰
